UNITED STATES PATENT OFFICE.

JOSEPH ARTHUR DAOUST, OF MONTREAL, QUEBEC, CANADA.

LOCKING DEVICE FOR RAILWAY SWITCHES.

1,413,010.

Specification of Letters Patent. Patented Apr. 18, 1922.

Application filed October 20, 1921. Serial No. 509,146.

To all whom it may concern:

Be it known that I, JOSEPH ARTHUR DAOUST, a subject of the King of Great Britain, residing at Montreal, Province of Quebec, Canada, have invented certain new and useful Improvements in Locking Devices for Railway Switches; and I do hereby declare that the following is a full, clear, and exact description of the invention, such as will enable others skilled in the art to which it appertains to make and use the same.

The present invention relates to new and useful improvements in locking devices for railway switches.

The primary object of the invention is the provision of a locking device for railway switches so constructed as to prevent unauthorized opening or closing of the switch without necessitating the use of the usual key actuated locks.

Another object of the invention is the provision of a locking device in which the handle portion thereof is held in position by a concealed locking apparatus which can only be actuated by the use of an authorized person or person instructed in the use of the same.

A further object of the invention is the provision of a locking device for railway switches such as above referred to and which will be comparatively simple and inexpensive to manufacture, reliable and efficient in use, and readily operated.

Another object of the invention is the provision of an additional locking means to prevent movement of the bell crank lever.

With the above and other objects in view, the present invention resides in the novel features of construction, formations, combinations and arrangements of parts to be hereinafter more fully described, claimed, and illustrated in the accompanying drawing, forming a part of the present application, and in which:

Figure 1 is a side elevation of a switch including the operating arm having the invention applied thereto;

Figure 2 is a longitudinal sectional view taken through the arm showing the latter in its lowermost position;

Figure 3 is a similar view showing the arm raised;

Figure 4 is a sectional view taken through the arm in the position shown in Figure 2, on a plane at right angles to the plane of the arm;

Figure 5 is a similar view taken through the arm in the position shown in Figure 3;

Figure 6 is a view showing the locking pin in engagement with the slidable operating rod; and,

Figure 7 is a similar view showing the sliding operating rod released.

Referring now to the accompanying drawing by corresponding characters of reference throughout the several views, the numeral 6 designates in general the rotating operating member of a switch which is mounted in the standard 7 which is provided at one side thereof with a laterally extending bifurcated arm 8 within which the usual switch lever 9 may be inserted.

The central portion of the lever 9 is enlarged at 10 and provided with a recess 11 in which a bell crank lever 12 is pivotally mounted as at 13. The free end of the bell crank lever is provided with a finger piece 14, while the opposite end thereof is pivotally connected at 15 to the curved lower end of a slidably operating rod 18 held normally in one position by a spring 19. A latch member is shown at 20 and is pivoted at 21 within an enlarged recess 22 provided in the upper end of the lever 9. The lower end of the lever 20 is provided with an offset extension 23 which is pivotally connected at 24 to the upper end of the rod 18, while the upper terminal of the latch 20 carries a locking pin 25 which projects through an opening 26 formed in the side of a lever 9 into a recess 27 provided in one side of the arm 8. Obviously when the locking pin 25 is in engagement with the recess 27, as shown in Figures 2 and 4, the switch lever 9 will be locked against any undesired or unauthorized movement.

As an additional means for locking the slidable operating rod to prevent any unauthorized use of the switch, this rod 18 is provided with an opening 30 provided in one side thereof for engagement with a sliding

pin 31. This pin 31 is provided at its upper edge with rack teeth 32 for engagement with the pinion 33 which is disposed in mesh therewith and which is carried by a shaft 34. 5 An arm 35 extends from the pinion 33 and is connected to a push rod 36 provided at its lower end with a push button 37 which is normally held in locking position by a spring 38. An authorized person may be instructed 10 to operate the device as follows:

The operator first presses inwardly on the push button 37 which forces the push rod 36 upwardly rotating the pinion 33 in such direction as to move the pin 31 outwardly 15 out of engagement with the notch 30. The handle is then grasped in one hand of the operator who next inserts the fingers of the opposite hand into the recess 10, pressing against the finger piece 14 which draws the 20 rod 18 downwardly against the tension of the spring 19 and moves the locking pin 25 from the position shown in Figure 4 out of engagement with the recess 27, as shown in Figure 5. This permits the lever 9 to be 25 raised out of engagement with the bifurcated end of the arm 8 and to be turned in the desired manner to operate the switch. A plate 29 is pivoted as at 39 within the recess 22 and is designed to swing by gravity in 30 front of the opening 27 when the lever 9 is moved to raised position to prevent the entrance of the pin 25 within the opening 27. This prevents the pin 25 from extending beyond the side of the lever and interfering 35 with the lowering of the lever from the position shown in Figure 3 to that shown in Figure 2, but when the lever is moved to the position shown in Figure 2 from that shown in Figure 3, the plate 29 will spring 40 by gravity out of the path of the opening 27 permitting the pin 25 to again engage the said opening and lock the lever 9 against movement.

From the foregoing description, taken in 45 connection with the accompanying drawing, it will be manifest that a locking device for railway switches is provided, which will fulfill all of the necessary requirements of such a device, and it should be understood in 50 this connection, that various minor changes in the specific details of construction can be resorted to within the scope of the appended claims without departing from the spirit or sacrificing any of the advantages of the 55 invention.

Having thus fully described the invention, what I claim as new and desire to protect by Letters Patent is:

1. The herein described locking device for 60 switches including a concealed locking pin and a concealed lever for actuating the same.

2. The herein described locking device for switches including an operating lever, a

locking pin mounted therein, and a concealed lever operatively connected thereto. 65

3. The herein described locking apparatus for switches including a switch operating lever, an arm for engaging the same, said arm having a recess formed therein, a locking pin mounted within the lever for projection into the recess in the arm, and a lever for actuating said pin. 70

4. The herein described locking device for switches including in combination with 75 a switch lever a locking pin mounted in the lever, a bell crank lever for actuating the pin, a latch supporting the pin, a spring actuated rod connecting the latch and bell crank lever, and an arm for engagement 80 with the lever, said arm having a recess formed therein for receiving the locking pin.

5. The herein described locking device for switch levers comprising the combination 85 with a lever and an arm having one end bifurcated to receive the lever, said arm having a recess formed therein, a recess formed within the lever, a bell crank lever mounted in said last mentioned recess, a locking pin mounted within the lever for engaging the recess in the arm, a latch pivoted within the lever and supporting the pin, a spring actuated rod connecting the bell crank lever with said latch, and a pivoted swinging plate movable into and out of the path of the locking pin, substantially 95 as and for the purposes set forth.

6. The herein described locking apparatus for switches including a switch operating 100 lever, an arm engaging the same, said arm having a recess formed therein, a locking pin mounted within the lever for projection into the recess in said arm, a lever for actuating said pin, and an additional locking means for said lever. 105

7. The herein described locking device for switches including the combination of a switch lever, a locking pin mounted in said lever, a bell crank lever for actuating the 110 pin, a latch supporting the pin, a spring actuated rod controlling the latch and bell crank lever, an arm for engagement with said lever, said arm having a recess formed therein for receiving the locking pin, said 115 spring actuated rod having a recess formed therein, a second locking pin engaging the recess in said rod, and means extending through the end of the switch lever for actuating the second mentioned locking pin, 120 substantially as and for the purposes set forth.

8. The herein described locking devices for switches including a switch lever, a locking pin mounted in said lever, a bell crank 125 lever operatively connected to the pin, a latch supporting the pin, a spring actuated rod connecting the latch and the bell crank

lever, an arm engaging the lever, said arm having a recess formed therein for receiving the locking pin, the spring actuated rod also having a recess formed therein, a second locking pin for engagement with the recess in the spring actuated rod, rack teeth formed upon the second mentioned locking pin, a pinion meshing with the rack teeth of said pin, an arm extending from the pinion, a

push rod secured to the arm and extending through the switch lever, a push button secured to the push rod, and a spring engaging the same, substantially as and for the purposes set forth.

In witness whereof I have hereunto set my hand.

JOSEPH ARTHUR DAOUST.
